Primary Examiner — Cathron Brooks*Assistant Examiner* — Sydney R Buffalow(74) *Attorney, Agent, or Firm* — Greenberg Traurig LLP;
Franklin D. Ubell(57) **CLAIM**

The ornamental design for a central color center display, as shown and described.

DESCRIPTION

FIG. 1 is a side perspective view of the central color center display; and,

FIG. 2 is a front view of the display.

The broken lines shown in the drawings are included for the purpose of illustrating portions of the display that form no part of the claimed design.
